UNITED STATES PATENT OFFICE.

WILLIAM VAUGHAN DEEBY, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CROWNING MACHINE.

Application filed January 8, 1923. Serial No. 611,495.

This invention relates to improvements in crowning machines and has particular reference to a hand-operated machine for applying sheet-metal crowns to bottles or other containers which are formed to receive such crowns.

The object of the invention is to provide a hand crowning machine that shall be exceedingly simple in construction, reliable in its operation to meet the demands of small bottling establishments and which may be readily and quickly adjusted for operation on bottles of different sizes.

The invention is illustrated in the accompanying drawings, wherein,—

Fig. 1 shows in perspective, the preferred form of a machine embodying the invention.

Fig. 2 illustrates the same in central vertical section.

Fig. 3 shows a horizontal sectional view through portions of the machine, the section being taken on the line 3—3 of Fig. 2.

Fig. 4 illustrates a cross-sectional detail through the same parts as the same would appear if viewed on the line 4—4 of Fig. 3.

Fig. 5 shows the complete machine in top view.

Fig. 6 illustrates a cross-sectional detail through the column as viewed on the line 6—6 of Fig. 2 and shows the bottle guide and clamp in top view.

Fig. 7 shows the detached crown platform in perspective.

Fig. 8 illustrates a horizontal sectional view of the parts as viewed on the line 8—8 of Fig. 2.

Figs. 9 and 10 show two vertical sectional details to illustrate the action of the presser foot on a crown prior to the crimping of the latter into engagement with the mouth of the closure.

Figs. 11 and 12 illustrate two additional sectional details to show the crimping operation of the parts.

Fig. 13 shows a vertical sectional detail through the spring cage and adjacent parts as the same would appear if viewed on the line 13—13 of Fig. 8.

Fig. 14 illustrates an enlarged central vertical section through the throat devices

and the crown-platform and shows a crown in place on the latter, and

Fig. 15 shows a slightly modified form of structure in that the base and column are omitted and a bracket attached to a wall or other vertical support substituted.

Referring to the drawings, and particularly Figs. 1-2 and 5 thereof, the numeral 20 designates a base or platform which is designed to seat on a bench or table and on the upper side of which there is a socket or recess 21 in which a pad or cushion 22 is retained. This pad or cushion forms a supporting surface for the bottom of a bottle or container 23 which is to be crowned or capped.

At the rear of the pad or cushion, the base is provided with a vertically-extending head 24 with a vertical socket therein. This head is provided at the rear side with a vertical slot which opens all the way through from the rear to the socket and on each side of the slot there is a boss 25 through which bosses a binding screw 26 may be passed, whereby to slightly spring the two sides of the head and draw them together when the screw 26, is turned in one direction. The purpose of this construction is to sustain a tubular support 27 by inserting the lower reduced end thereof in the socket and then clamping the same in place by means of the screw.

The support 27 is provided at its rear with a vertical groove or spline 28 for a purpose presently to be explained.

An adjustable bottle guide or gauge 29 is carried by the head 24 and projects over the base above the pad for the purpose of serving as a gauge to properly position the bottle beneath the crowning devices which latter will presently be described.

An adjustable head 30 has a split sleeve portion 31, which engages the tubular support 27, and which is clamped about the support by means of a lever clamp-screw 32. The head and sleeve are held in alinement with the bottle guide and pad by means of a circular key 33, which latter is carried on the screw-part of the clamp-screw 32 and which key is located in the slot of the sleeve

so it may enter the spline 28 in the rear of the column or tubular support. By this means this arrangement of sleeve, clamp-screw and key, the head may readily be 5 adjusted vertically on the support but the sleeve and head be prevented from rotation on the support.

Obviously, the purpose in providing vertical adjustment for the head on the support 10 is to set the head with respect to the pad to suit the height of the bottles or containers which are to be crowned or capped.

The head has a tubular portion 34 which forms a housing and carrier for the mechanism that seats and crimps the crown into 15 locked engagement with the bottle or container.

The housing is provided with upper and a lower bearing bushings 35 for a purpose 20 that will presently be explained.

The interior of the housing forms a vertical bearing for a crowning-ram or throat-carrier 36, the upper end of which latter is provided with a central recess or chamber 25 37 having an annular shoulder 38 therein. From the shoulder 38 downwardly, the crowning-ram has a central guide passage 39, while below the said passage there is another central passage 40 which is larger 30 in diameter than the guide-passage.

A support washer 41 has position in the lower end of the upper ram-chamber 37 and this washer normally seats on the annular shoulder 38, as clearly shown in Fig. 2 of 35 the drawings.

In the same ram-chamber 37 there is located a presser-foot spring 42 whose lower end seats on the washer 41 and whose upper end is compressed, more or less, by an adjustable plug 43 which screws down into the 40 said chamber.

In the narrower central guide-passage 39 of the crowning-ram there is located a plunger 44, with a reduced upper end 45 45 which provides an annular shoulder 46 around the base of the said reduced end. This annular shoulder 46 has position directly beneath the washer 41 while the reduced end 45 extends up through the washer 50 and enters the central opening formed by coils of the spring.

It will therefore be clearly seen that if the plunger 44 be held stationarily while the ram 36, is moved downwardly, that the plug 43, 55 will compress the spring 42, and washer 41, will then be held down on the plunger shoulder 46, while the ram-shoulder 38 will drop away from the washer.

The presser-foot spring 42 is so designed 60 that its coils will close one upon the other when the throat 54, which moves with the ram 36, has moved down over the cap on the bottle a sufficient distance for properly crimping the crown while the plug 43 enables a variation to be made in the expan-

sion of the spring so that the exact relative positions of the throat and presser-foot may be attained at the time the coils of the spring close together.

The plunger 44 extends down through the 70 enlarged chamber 40 and has a circular flange or disk 47 thereon which has position at the lower end of said chamber, while beneath the flange, the plunger carries what I term a presser foot 48.

The lower end of the crowning-ram has an enlarged head 49 with an external annular supporting-flange 50 near the lower edge thereof and at diametrically-opposite sides the head is provided with vertical perforations 51 which extend up therethrough and which perforations pass through a portion of the supporting flange, as shown in Fig. 4 of the drawings.

The lower end of the crowning-ram 36 85 and its head 49 have an annular recess 52 into which is fitted loosely, a crimping-throat 54.

This crimping-throat has a central tapered passage 55 therethrough, from bottom 90 to top, so that it is narrower at the top than at the bottom, and this tapered passage 55 normally contains the presser-foot 48 which hangs pendent from the lower end of the plunger 44.

Between the upper side of the crimping-throat and the lower face of the circular flange 47 on the plunger, there is interposed an inverted cup-washer 56, and the presser-foot 48, extends down through this washer 109 while the upper side of the washer forms a support on which the circular flange 47 of the plunger may seat when the parts are assembled and in the normal position, as clearly readable in Fig. 2.

The plunger 44 with its flange 47, presser foot 48, cup-washer 56 and crimping-throat 54 are all insertable within the lower end of the crowning-ram, and all of these elements are held up in the ram by means of a crown-platform 57, which latter is shown in perspective in Fig. 7 of the drawing.

The crown-platform has the form of a plate with a central perforation 58 in its under side and with a horizontal recess 59 115 in its upper side, which recess extends laterally from a point slightly at the rear of the central perforation and opens at, or slightly to one side of the front beneath the housing 34. By preference, this platform is 120 provided with a forward extension or shelf 60 which projects beyond the circumference of the head 49 but is spaced below the latter, as clearly shown in Fig. 14 of the drawing, and the upper surface of this shelf and the bottom surface of the recess 59 are in alignment, and lie in a horizontal plane below the crimping-throat 54 and presser foot 48.

By again referring to Fig. 7 of the draw- 130

ing, it will be noted that the recess 59 forms a slight shoulder or ledge 61 at opposite sides and the rear of the central bottom-perforation 58, so that the flange or skirt 62 of a 5 crown 63, may have sufficient support on said ledge to sustain the crown directly over the perforation 58 as long as that skirt is in the flared condition as prior to its attachment to a bottle neck.

10 The crown-platform is provided with a vertically-extending pin 64 at each of two opposite sides of the recess 59 each of which pins is provided with a notch 65 in its outer side.

15 When the platform is seated up against the bottom end of the ram-head and the bottom side of the crimping-throat 54, the pins 64 extend up through the vertical perforations 51 and above the annular supporting- 20 flange 50, and the notches 65 in the pins also have position above said flange.

A locking-ring 66, see particularly Figs. 3, 4 and 5 of the drawings, is located on the flange 50, and has notches 67 at diametrically-opposite sides of its inner circumferential wall. The arrangement of these ring-notches 67 is such that the ring may be turned around the exterior of the head until these notches both register with the pins 64 30 which project up from the crown platform, whereupon those pins and the platform may be seated up close against the bottom of the head and the under side of the crimping-throat 54.

35 When the pins 64 have thus been passed through the ring-notches, the ring will then register with the side notches 65 in the pins. By then rotating the ring 66 slightly, its notches 67 will be moved laterally from the pins and the inner circumferential wall of the ring 66 will extend through the pin-notches as shown in Fig. 4, and securely lock the pins and the crown-platform in place.

In the operation of the machine it is necessary to impart a vertical reciprocation to the crowning-ram 36, for purposes presently to be explained,—the means however for effecting this movement of the ram will now be explained, particular reference being made to Figs. 2, 5, 8 and 13 of the drawings.

At the rear, the crowning-ram is provided with a vertical rack 68 whose teeth are exposed to a machined recess 69 in the head 30 between the sleeve portion 31 and tubular 55 portion 34.

The wall of the head 30 at one side thereof is provided with a circular bearing-opening 70 (see Fig. 8) while at the opposite side the head has a circular flange 71 in which a 60 spring-cup or cage 72 is inserted. This cup or cage is provided with a radial slot 73, (see Fig. 13) so that the outer end of a flat coiled spiral spring 74 may be engaged in said cup or cage-slot and held therein.

Extending horizontally through the head 65 recess 69 and the cup or cage 72 there is a horizontal gear-shaft 75, one end 76, of which has bearing in the opening 70 in the head-wall, while the other end of said shaft extends through and has bearing in the 70 closed end wall of the cup or cage, as clearly shown in Fig. 8.

The gear-shaft 75 carries a gear 77 while a reduced portion of said shaft extends into the spring-cup or cage 72 and has a groove 75 78 therein, as shown in Fig. 13, in which the inner end of the spring 74 is secured.

It will thus be understood that the outer end of the spring 74 is attached to spring cup or cage 72, while the inner end of said 80 spiral spring is attached to the gear-shaft 75. By rotating the cup the spring may be placed under sufficient tension, while the crowning-ram 36 is elevated, to hold the latter in that 85 elevated position, and to keep the spring in this partly wound condition, I provide a key 90 pin 79, which passes through perforations 80 and a passage 81,—the perforations being in the head-flange 71 and the passage being in the end wall of the cup 72, and both perforations and passage being in alinement or registration, when the cup has been turned sufficiently to place the spring under the required tension.

The outer end of the gear-shaft 75, has a 95 tapered and squared extremity 82 with a threaded socket in the end thereof and on this squared end, I place an arm 83 having a handle-socket 84 at its outer end in which an operating handle 85 is seated.

100 A wing-bolt 86 screws into the socketed end of the gear-shaft and holds the arm 83 thereon.

By reference to Figs. 1 and 15 of the drawings, it will be noted that the large end 105 of the handle-socket 84 is provided with two diametrically located pins 90. These pins enable the socket-member to be utilized as a spanner wrench during the adjustment of the spring-cage 72, as will now be explained.

110 By again referring to said Figs. 1 and 15, it will be noted that the spring-cage 72 is provided with two holes or sockets 91 on opposite sides of the axis of the cage and therefore diametrically-opposite each other. The distance between the centers of these holes or sockets 91 and the distance between the centers of the pins 90 on the handle-socket are equal so that if the handle-socket 115 84, be removed from the shaft 75 and the handle 85 be withdrawn from said socket 84, the latter may be seated against the end wall of the cage 72 and the pins 90 will register with and enter the holes 91 in the cage so 120 that the handle-socket will engage the cage like a spanner wrench and the cage may thus 125 be turned or rotated with or against the ten-

sion of the spring 74 until the key-pin 79 can be inserted or removed as desired and no separate spanner-wrench tool is required.

In some instances it has been found desirable to provide a wall type of supporting means for the head 30 and to do this I simply omit the tubular support 27 and the base 20 and substitute a bracket 89, as shown in Fig. 15 of the drawing, which bracket will receive the split sleeve portion 31 of the head.

When the head 30 and sleeve 31 are supported by the wall bracket a suitable shelf or other support for the bottle to be crowned will be provided and in view of the fact that the centers between the sleeve 31 and tubular portion 34 are maintained, a bottle of any height, and of any diameter that can be used on the base 20 in the structure of Fig. 1 can be operated upon in the wall-bracket form.

The operation of the machine is as follows:

A bottle or container 23, after having been filled and in readiness for the crown, is placed on the pad 22. The head 30 is then adjusted vertically on the standard 27, to suit the height of the bottle and those of substantially the same height,—slight variations in the heights being immaterial.

The crown 63 is placed on the projection 60 of the crown-platform and a second crown when placed beside the first crown will push the latter into the recess 59 and over the opening 58, where it will be sustained by the ledges 61.

Operating handle 85 is then swung forward which will cause the gear-shaft 75 to turn the gear 77 and thereby move the 40 crowning-ram 36 downwardly.

As the ram moves down, the crown-platform the crimping-throat 54, the plunger 44 and presser-foot 48, will all move down, as they are all carried by the ram.

45 As the crown-platform lowers, the bottle-mouth will be entered in the central perforation 58 of the platform and the crown 63 which is in position in the recess 59 will seat on the bottle-mouth.

50 The ram continues to move down and the presser foot 48 seats on top of the crown and as this downward movement continues, the foot 48, and plunger 44, will remain stationary while the presser-foot spring 42 will

55 gradually compress as the ram and the plug 43 continue said movement. The compression of the spring 42 seats the sealing gasket 87 on the mouth of the bottle and in readiness for the locking of the crown. The position of the parts as this stage of the operation will be substantially as shown in Figs. 9 and 10 of the drawing, wherein the crown is located at the lower larger end of the crimping-throat passage 55.

65 The ram 36 continues to move down, leav-

ing the plunger 44 and presser-foot 48, stationary, but carrying the crimping-throat 54 with it, and during this further or final movement, the tapered wall in the throat-passage 55, will force the flange or skirt 62 of the crown inwardly into locking engagement with the bottle-neck and thus hold the sealing-gasket 87 in sealing contact with the bottle-mouth,—the parts at the conclusion of the locking or crimping operation being substantially as shown in Figs. 11 and 12 of the drawings.

Assuming that the plug 43 has been properly adjusted, the end of the crowning operation will find the crown properly crimped and the coils of the presser-foot spring 42 closed together so that any further downward pressure exerted by the crowning ram will only result in compressing the sealing gasket in the crown and wedging of the bottle-neck in the throat is prevented when the spring-coils close together.

During the forward movement of the handle 85 and the downward movement of the ram, the spring 74 in the cup or cage 72 will be wound sufficiently to return the parts to the normal position shown in Figs. 1 and 2 of the drawing as the operator relieves the handle so that the operator merely holds the handle to prevent it from swinging back uncontrolled.

When the crimping operation is completed, the diameter of the periphery of the crown-flange or skirt 62 will have been reduced to a point where it will be less than the diameter of the perforation 58 in the crown-platform, so that when the handle 85 is returned and the ram raised, the crowned bottle-neck will withdraw through the opening 58 of the crown-platform.

When the operating handle 85 is first released the spring 42 in the ram performs its second function of ejecting the crimped crown from its wedged position in the crowning throat.

It will be noted that by partly rotating the locking ring 66 until the slots 67 in the ring are brought into register with the notched pins 64 of the crown-platform 57, that the entire platform may be detached, and upon its removal the crimping-throat 54, cup-washer 56, presser-foot 48 and plunger 44, may all be taken out bodily from the interior of the ram 36.

In this way crimping-throats of different sizes, together with a change of other parts necessary to provide for a change from one size crown to another size may readily be made without disturbing the presser-foot spring in the upper end of the ram.

In some instances it has been found desirable to utilize this hand-operated machine for applying crowns of the largest sizes to bottles which require crowning rams having lower ends of considerable size. In such

case the spring-cage can be removed by the aid of the handle-socket as a spanner wrench, the gear-shaft can be removed and the complete crowning-ram assembly changed to meet the condition and no tool is necessary other than the combined handle-socket and spanner-wrench.

Having described my invention, I claim,

1. In a bottle-crowning machine the combination with a stationary bottle-sustaining device, of a vertical support extending above the bottle-sustaining device, a head adjustably carried on the vertical support said head having a vertical bore therein, a ram movable vertically in the bore of the head said ram having an upper spring chamber, a lower plunger-chamber and a reduced guide-passage between said two chambers, a plunger extending longitudinally in the ram from the plunger-chamber, through said guide-passage and having its upper end exposed in the upper spring-chamber,—said plunger having an annular enlargement in the lower end of the plunger-chamber, a cup washer beneath said enlargement, a presser foot at the lower end of the plunger, a crimping-throat beneath the cup-washer and around the presser foot and a spring in the upper chamber of the ram to press the plunger down.

2. In a bottle-crowning machine the combination with a support, of a head carried by the support said head being provided with a tubular housing, a crowning ram in the housing and having a rack at one side thereof, crown-applying devices carried by the ram, a shaft and gear means for actuating the ram, a cup entering the side of the head and having spaced-apart sockets in its outer side, a spring enclosed in the cup, said spring having one end attached to the cup and its other end attached to the shaft, a handle-socket at the outer end of the shaft said socket being provided with spaced-apart pins to engage the sockets in the cup and serve as a spanner-wrench to turn the cup and place the spring under tension.

3. In a crowning-head structure for bottle-crowning machines the combination with a head having a vertical tubular guide-passage therethrough, of a vertically movable crowning-ram having a sliding fit in the tubular passage and provided with a central spring recess in its upper end and a central bearing passage extending down from the spring recess, a plunger fitting the bearing passage in the ram,—said plunger having its upper end exposed in the spring-recess, a spring in the recess of the ram and normally held disengaged from the upper end of the plunger, a presser-foot at the lower end of the plunger and a crowning-head at the lower end of the ram whereby the weight of the plunger will normally keep it away from the action of the spring but will be acted upon by the spring after the presser-foot seats against a bottle crown at the beginning of the crowning operation.

4. In a crowning-head structure for bottle-crowning machines the combination with a head having a vertical tubular guide-passage therethrough, of a vertically movable crowning-ram having a sliding fit in the tubular passage and provided with a central spring recess in its upper end and a central bearing passage extending down from the spring recess,—the central bearing passage being of lesser diameter than the spring-recess whereby to form an annular shoulder around the passage and at the base of the recess, a plunger fitting the bearing-passage of the ram and having its upper end arranged with a shoulder which may be projected into the spring-recess, a spring in the recess of the ram and normally sustained from the annular shoulder of the ram around the bearing passage and upper plunger-end whereby the plunger will normally be free of the spring pressure, a crowning-head at the lower end of the ram and a presser-foot at the lower end of the plunger.

In testimony whereof I affix my signature.

WILLIAM VAUGHAN DERBY.
